UNITED STATES PATENT OFFICE.

WILLIAM S. COOPER, JR., AND JOHN DORRICOTT, OF PHILADELPHIA,
PENNSYLVANIA.

WATER-CLOSET TANK.

SPECIFICATION forming part of Letters Patent No. 688,720, dated December 10, 1901.

Application filed November 16, 1900. Serial No. 36,655. (No model.)

To all whom it may concern:

Be it known that we, WILLIAM S. COOPER, Jr., a citizen of the United States, and JOHN DORRICOTT, a subject of the Queen of Great Britain, both residing in the city and county of Philadelphia, State of Pennsylvania, have invented a new and useful Improvement in Water-Closet Tanks, of which the following is a specification.

10 Our invention relates to water-closet tanks of that class in which is employed a siphon having a checking device located within the down-leg of the apparatus; and the object of our invention is to dispense with the gurgling noise or sound heretofore incident to such constructions. We provide for the admission of the air into the down-leg at a point below the bridge formed by the junction of the up-leg and down-leg instead of above said bridge, 15 as heretofore, employing an auxiliary vent below the bridge and above the outlet of the downwardly-extending tube of the checking device within the down-leg of the apparatus.

20 It further consists of novel details of construction, all as will be hereinafter described, and particularly pointed out in the claims.

Figure 1 represents a vertical sectional view of a water-closet tank embodying our invention. Fig. 2 represents a section on line *xx*, 25 Fig. 1. Fig. 3 represents a section on line *yy*, Fig. 1.

Similar numerals of reference indicate corresponding parts in the figures.

Referring to the drawings, 1 designates the 30 base of a tank 2, the latter having located therein the outlet 3, which latter has a seat 4, in the present instance attached to or integral therewith, for the packing or washer 5, which is held between the flange-nut 6 and the threaded plunger-head 7, said nut 6 having a downward annular extension 8, which is provided with the bars 9 therein, whereby 35 the valve will be properly guided in its upward-and-downward movement.

40 45 50 10 designates an inner shell or wall whose lower extremity engages the plunger-head 7, the upper extremity of said shell engaging the suitable portion of the cap or casting 11, the latter supporting the outer shell 12, whose lower extremity terminates a short distance above the head 7, whereby it will be seen that

an up-leg 13 is formed through which water can flow in the direction of the arrow *a* upwardly through the suitable ports 14 in the cap 11 over the bridge 15, as indicated by the arrow *b*, into the down-leg 16, which is formed by the space within the inner shell 10.

55 17 designates a checking-tube which is provided with the ports 18, said checking-tube terminating at a suitable point in the lower portion of the down-leg 16, the upper extremity of said checking-tube being suitably supported in the cap or casting 11 and communicating, by means of the passage 19, with the downwardly-extending pipe 20, which forms 60 part of the checking device, whose lower extremity terminates at a suitable point near the bottom of the tank 1.

The cap or casting 11, the up and down legs 13 and 16, and the washer 5 and its adjuncts depend from the lever 21 by means of the connection 22 common to said lever and to the eye 23 of the leg 24, projecting from said cap or casting 11, said lever 21 being suitably fulcrumed.

70 75 We deem it important that the auxiliary vent-ports 18 be below the bridge and between the same and the lower or outlet end of the tube 17, as shown, for by this disposition of the vent the air is admitted into the 80 down-leg at a point below that at which the water enters said down-leg, and the noise caused by the mixing of the air and water is not heard as it is when the mixing takes place above the bridge.

85 The operation is as follows: The operation of unseating the valve is effected by imparting the proper movement to the lever 21, whereby the washer 5 is raised from its seat and the water passes out through the outlet 90 3. Upon releasing the lever the washer reseats, and by reason of the partial vacuum formed within the up-leg 13 and the down-leg 16 it will be apparent that water will flow upwardly in the up-leg 13 and thence through 95 the port 14 into the down-leg 16, which operation will take place until air is admitted to the lower extremity of the outer checking-tube 20, said air passing through the ports 18 of the checking-tube 17 at the proper time, 100 and thereby causing the breaking or cessation of the perfect siphon action, while a par-

tial siphon action will continue until the water-level of the water in the tank is below the lower extremity of the tube 17, when the siphon action will entirely cease, the latter (a partial siphon) constituting the afterfill.

It will be apparent from the foregoing description that we have produced a very simple and effective apparatus for the purpose named wherein we dispense with floats or tripping mechanism and their adjuncts which have been heretofore employed in devices of this character.

Having thus described our invention, what we claim as new, and desire to secure by Letters Patent, is—

1. In a water-closet tank, an up-leg and a down-leg and a bridge formed thereby, a checking device having an outlet below said bridge and an auxiliary vent for said checking device above said outlet and also below said bridge, whereby air is admitted at the proper time into said down-leg, only below the bridge so that the gurgling noise is prevented.

2. In a water-closet tank, an outlet therefor, a plunger, an up-leg and a down-leg and

a bridge formed thereby, and a checking device consisting of a tube outside of said plunger and a tube extending downwardly in said down-leg, the outlet of the latter being below the bridge, said downwardly-extending tube being provided with an auxiliary vent above its outlet and below said bridge, whereby air is admitted into the down-leg below the bridge and below the point of ingress of the water and the gurgling noise prevented.

3. In a water-closet tank, a cap, an inner and an outer shell depending therefrom, and a bridge formed thereby, a checking-tube depending from the cap within the inner shell and having an auxiliary vent between its ends and below said bridge, an outer checking-tube extending outside the outer shell and communicating with the inner checking-tube through a port in said cap, and a plunger carried by the lower end of the inner shell.
